WINDOW SCREEN AND MOUNTING
THEREFORDock G. Horton, Birmingham, Ala., assignor of
one-half to Forrest T. Holsumbuck

Application January 23, 1941, Serial No. 375,682

2 Claims. (Cl. 156—14)

My invention relates to improvements in window screens and mountings therefor, the principal object in view being to provide a burglar-proof mounting for a screen which is equipped for swinging outwardly of a window frame for access to the window from the outside thereof, as for cleaning, is adapted to be locked in the window frame against being swung outwardly from the outside of the window and is adjustable in accordance with variations in standard sizes of window frames.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a view in front elevation of the preferred embodiment of my invention,

Figure 2 is a view in vertical section taken on the line 2—2 of Figure 1 and drawn to an enlarged scale,

Figure 3 is a view in rear elevation of the mounting frame detached from the window frame and with the screen removed therefrom,

Figure 4 is a fragmentary view in horizontal section taken on the line 4—4 of Figure 2,

Figure 5 is a fragmentary perspective view of the screen,

Figure 6 is a view in perspective of one of the locking members, and

Figure 7 is a view in perspective of one of the combined coupling and keeper members.

Referring to the drawings by numerals, I have shown therein my invention as mounted in the usual window frame 1 having a raised stool cap section 2, a sill 3, a head stile 4, inner and outer sash stops 5, 6, a parting strip 7, in which frame is mounted the usual upper and lower sashes 8 and 9.

According to my invention, a screen mounting frame 10 is provided of rectangular form and of angle iron and which is adapted to fit in said window frame 1 outside the sashes 8, 9, and against the outer sash stop 6 channel side innermost.

The upper and lower ends 11, 12, of the screen mounting frame 10 are transversely divided, or split, as at 13 so that said frame comprises two vertically divided sections which may be adjusted laterally to provide for a snug fit of the same in standard sizes of window frames varying slightly in width due to faulty mill work, warping or the like. The sides 14, 15, of said mounting

frame 10 are similarly divided, or split, transversely, as at 16, adjacent the upper end 11 of the frame so that said frame also comprises upper and lower sections adjustable to extend or shorten said frame vertically for the same purpose as above set forth relative to the described lateral adjustment. The divided ends of the upper and lower ends 11, 12, of said mounting frame 10, and the divided ends of the sides 14, 15, are adjustably coupled together by means presently described.

Fitting in the described screen mounting frame 10 from the rear or inner side thereof, is a screen 17 comprising the usual sheet of screening 18 having crimped around the edges thereof a sheet metal reinforcing frame 19.

Short angle iron coupling bars 20 in the screen mounting frame 10 couple the divided ends of the upper and lower ends 11, 12, of said frame 10 together and also the divided ends of the sides 14, 15, of said frame 10, said bars 20 being welded, as at 21, to said ends 11, 12, and to the sides 14, 15, on one side of the splits and secured to said ends and sides on the other sides of the splits by bolts 22 extending through suitable slots 23 in said bars, whereby the described adjustments of said frame 10 may be made in a manner which will be clear. The coupling bars 20 bear against the reinforcing frame 19 of the screen 17 and thereby function as keepers securing the screen 17 in the mounting frame 10.

A pair of strap iron hangers 24 are suitably secured, as by welding, not shown, to the outer face of the upper end 11 of the screen mounting frame 10 and which are slotted, as at 25, for the extension therethrough of the usual hanger hooks 26 mounted on the frame 1, whereby said mounting frame 10 is suspended from said frame 1 for swinging out of and into the latter.

A pair of bar-like locking members 27 of flexible metal are suitably secured, as by welding, not shown, to the lower end 12 of the screen mounting frame 10 and adjacent opposite sides 14, 15, of said frame, to extend inwardly of the window frame 1, said members 27 having upstanding right angled, inner end extensions 28 abutting the stool cap section 2 to limit swinging movement of the screen mounting frame 10 inwardly of the window frame 1, said extensions 28 forming hand grips by means of which the locking members 27 may be flexed upwardly for a purpose presently seen. The locking members 27 are provided with keeper lugs 29 on the under sides thereof, and the sill 3 with complementary notches 30 in which the lugs 29 enter with

a snap action when said mounting frame 10 is swung inwardly of the window frame 1 into its limit of movement in that direction as established by abutment of the extensions 28 against the stool cap section 2, and whereby said mounting frame 10 is locked against being swung out of the window frame 1 from the outside of the window. By flexing the locking members 27 upwardly, the keeper lugs 29 may be lifted out of the notches 30 and said mounting frame 10 unlocked when desired.

In the rear of the screen 17 is a burglar-proof grid comprising an angle iron bar 31 extending across the mounting frame 10 substantially in the transverse center of said frame and having 15 right angled end extensions 32 bolted to the sides 14, 15, of said frame 10, as at 33.

A plurality of vertically disposed rods 34 of suitable metal are secured at their lower ends to the lower end 12 of said frame 10, said rods being spaced apart along said end 12 and preferably secured to the latter by setting the same in said end 12 and soldering therein, the solder not being shown. The rods 34 extend through the bar 31 and above the same and may be provided 25 with sharp upper ends 35.

It should be explained, that the bar 31 is transversely split, as at 35, and the sections thereof thus formed secured together by a slotted bar 36 and bolt 37 similar to bars 20 whereby said bar 31 may be extended or contracted in accordance with the lateral adjustment of said frame 10.

The foregoing will, it is believed, suffice to impart a clear understanding of my invention without further explanation.

Manifestly the invention, as described, is sus-

ceptible of modification without departing from the inventive concept, and right is herein reserved to such modifications as fall within the scope of the subjoined claims.

5. What I claim is:

1. In combination a screen mounting frame for use in a window frame comprising adjoining angle bar sections arranged end to end for adjustment and forming a rectangular structure, said sections being relatively adjustable to increase and diminish the size of said mounting frame, respectively, in accordance with variations in size of window frames of a given type due to manufacturing imperfections, a screen fitting in said mounting frame, and means to secure said sections together in adjusted relation comprising angle bars bridging the ends of adjoining sections, said bars being fixed to one of each of the adjoining sections and adjustably connected to the other adjoining section, said bars bearing against said screen to retain the same in said mounting frame.

2. In combination a screen mounting for use in a window comprising a rectangular frame of angle iron, a screen fitting in said frame, and a burglar-proof grid in said frame backing said screen and comprising a transverse bar extending midway across said frame and detachably fixed thereto, and vertical rods arising from the bottom of said frame and extending through said bar, said bar comprising a flange having right angled ends fitting in said frame and a right angled flange spaced at its ends from said right angled ends to fit between the inner edges of said frame.

DOCK G. HORTON.
